UNITED STATES PATENT OFFICE.

JOHN AUSTIN, OF FENELON FALLS, ONTARIO, CANADA.

LATCH AND LOCK COMBINED.

SPECIFICATION forming part of Letters Patent No. 405,241, dated June 18, 1889.

Application filed October 25, 1888. Serial No. 289,159. (No model.) Patented in Canada September 25, 1888, No. 29,904.

To all whom it may concern:

Be it known that I, JOHN AUSTIN, of Fenelon Falls, in the county of Victoria, in the Province of Ontario, in the Dominion of Canada, have invented certain new and useful Improvements in a Combined Latch and Lock, (for which I have received a patent of the Dominion of Canada, No. 29,904, dated September 25, 1888;) and I do hereby declare that the following is a full, clear, and exact description of the same, reference being had to the accompanying drawings, in which—

Figure 1 is a plan of the interior parts of my improved latch and lock in position as when operative by a knob-spindle. Fig. 2 is a like view of the same when the bolt has been retracted by the knob-spindle from the latched position; and Fig. 3 is a like view showing position of parts when the bolt has been operated by a key to lock the door.

The object of my invention is to improve the construction of combined spring latches and locks in which the bolt is operated by a knob-spindle and locked by projecting it from the latched position by a key.

My invention consists in the combination of parts, as hereinafter described, and pointed out in the claim.

1 is the case or shell of the latch and lock, 30 provided with a post 2, having a hole to receive a screw to fasten the cover to the case.

3 is a post on which is hung a pendulum 4, having posts 5 6 and a notch 7.

8 is a spindle-tappet journaled in the cover 35 and case, and provided with a square hole 9, to receive a knob-spindle for operating the latch. The spindle-tappet has two arms, the shorter one 10 engaging the pendulum 4 at notch 7 at the top end, and the longer arm 11

40 engaging the post 5 of the pendulum, so that by turning the tappet in either direction one of said arms will move the pendulum rearwardly in the lock-case adversely to the resistance of a spring projecting the latch to retract bolt 12, which is provided with a transverse slot *h* near the rear end, with which slot post 6 of the pendulum engages and supports the bolt horizontally. The opposite end of the bolt bears in an opening in the front edge

50 of the case in the ordinary manner.

The bolt near the middle is provided with

arms *a a'* at right angles to the bolt, one arm having an outwardly-turned end *b*, and the other an inwardly-turned end *b'*, the latter in engagement with the free end of a spring 55 13, which forces the bolt outwardly after being retracted by the pendulum, as before described. The other end of the spring is retained fixedly against a projection *c*, cast integrally with the lock-case, and said spring 60 is kept under tension by bearing against a dog 14 or other suitable resistance solid with the case; but any other arrangement of a spring to force the bolt outwardly may be adopted. The provision of the arms *a a'* to 65 the bolt allows it to be reversed for right and left hand locks.

d is a bearing cast with the lock-case, and on it the bolt frictionally slides; but such bearing, if desired, may be dispensed with. 70

The dog 14 is sleeved on a post 15, cast with the lock-case, and it has an arm *e*, which works through a slot in the top edge of the lock-case, and a hooked nose to engage with the upper turned end *b* of arm *a* of the bolt, 75 to prevent the bolt being retracted by turning the knob-spindle when the bolt is at the latched position, as shown in Fig. 1. When the dog is in engagement with the arm, the bolt is inoperative by a key. 80

17 is a post cast integrally with the lock-case, and 18 a slot in the bolt having a projection *g* on the upper side which engages one face of the post to limit the spring movement of the bolt when at the latched position. 85

The bolt is thrown to a locked position by a key entered at the key-hole 19, and engaging the bolt to lift the rear end, whereby the projection *g* will be lifted over post 17, and said rear end by gravity will then fall into 90 engagement with the opposite face of the post to prevent the bolt being retracted by turning the knob-spindle, and the knob-spindle will not be operative until the key again returns the bolt to its former position. The 95 lower end of the pendulum is engaged by the key simultaneously with said key lifting the bolt over post 17 to retract the bolt from the locked position.

I claim as my invention—

The combination, with the lock-case provided with posts 3, 15, and 17, of the pendu-

lum 4, hung to post 3, and having posts 5 6, the spindle-tappet 8, having arms 10 11, engaging with the pendulum, the bolt 12, having a slot *h*, engaging with post 6 of the pendulum, and a slot 18, having a projection *g*, engaging post 17 of the lock-case, and provided with arms *a a'*, the dog 14, sleeved on

post 15, and engaging one of said arms, and a spring 13, to move the bolt, substantially as set forth.

JOHN AUSTIN.
